UNITED STATES PATENT OFFICE.

SILAS CORDES, OF BOISE, IDAHO.

HEADLIGHT ATTACHMENT.

Application filed August 11, 1926. Serial No. 128,674.

This invention relates to improvements in co-pending application for headlight attachments, Serial No. 63,240, filed Jan. 23, 1926.

5 The main object of the present invention is to provide attachments for headlights of the "bullet" type which will permit the radiation of light laterally to the roadsides and at the same time eliminate the direct rays 10 to approaching drivers.

More specifically, the invention includes a detachable shell designed to be positioned within the conventional headlight of the type mentioned, which shell contains a plurality of vertical partitions for preventing the lateral diffusion of the light rays, the partitions also being provided with cutout portions for permitting the escape of certain light rays through lateral ports in the walls 20 of the lamps proper.

Reference will be had to the accompanying drawings forming a part of this specification and wherein like characters of reference designate corresponding parts 25 throughout the several views in which

Fig. 1 is a side elevation showing a portion of a motor vehicle, in elevation, with the lamp attached and the method of projecting the light to the front and side of the 30 road.

Fig. 2 is a top plan view of Fig. 1.

Fig. 3 is a sectional view through one of the lamps showing the shell with the partitions in position, the rays being directed 35 through one of the lateral parts, and

Fig. 4 is a front view of the lamp cut in two on a horizontal plan with the halves separated showing the location of the vertical partitions, the openings in the lower 40 side and certain partitions with parts of them cut away to permit the unobstructed passage of the light F.

Referring to Figs. 1 and 2; a motor vehicle is illustrated sufficiently to show the 45 position of the lamps and the direction of the forward and lateral rays therefrom. In these figures reference character A illustrates the radiator, B, the wheel, and C, the fender of a vehicle. The lamps are illustrated by 50 reference character E and disclose forward beams of light G and lateral beams, F. The lamps, which—as heretofore stated—are of the conventional "bullet" type, includes a lamp casing a, and a forward chamber b, which latter is adapted to contain the series 55 of vertical partitions hereinafter described.

In the lamp chamber a, the globe is illustrated at d, and a reflector i, is positioned rearward thereof to project the light through the lamp lens e. The shell b is provided at 60 one side with a lateral opening g, located sufficiently near the base to permit the rays from the lamp d to be projected at points approximately at the edge of the conventional road. 65

It will be well to note here that in outfitting a motor vehicle with the present type of lamp, it is usually advisable to provide one lamp with the lateral opening g to the right and another lamp with the lateral 70 opening g to the left, whereby the rays from the lamp through the openings will be projected to each side of the road. In some instances it may be preferred to only equip the right-hand lamp with a right- 75 hand opening, whereby the driver can observe only his side of the road. This selection of lamps, with the respective openings, is merely a matter of choice and discretion with the operators. The lamp proper 80 includes a casing a, in which is located the globe d and the reflector i, which latter is positioned to the rear of the globe. The lens e is positioned sufficiently rearward of the outer peripheral edge of the lamp shell 85 a to permit the arrangement of the threaded portion f, by means of which the forward body or the shell b is attached. The shell b is of a general cylindrical form gradually reduced at either end to present a neat appearance at the points of junction with the lamp a, and also at the forward end through which the rays are projected. Within the shell b are arranged a series of vertical partitions of various designs c suitably spaced 90 and extending longitudinally from end to end of the shell body. These partitions prevent a lateral filtering of the rays and cause a forward projection in a direct line and out of the optical range of an approaching 100 driver. To permit the projection of light to the sides of the motor vehicle, the lamps are provided with lateral openings, the right-hand lamp being provided with a right-hand opening and the left-hand lamp being 105 provided with a left-hand opening, whereby in the event that both lamps of a motor vehicle are equipped with the present attachment, the roadway is illuminated not only forwardly but also laterally a sufficient 110 distance to facilitate satisfactory driving. In order that the light rays from the globe

d may filter through the lateral openings *g*, the partitions in that side of the shell *b* adjacent the openings are cut away, the cut-out portions gradually increasing to accommodate the gradually increasing rays from the lamp.

It will be noted that the vertical partitions in that half of the lamp adjacent the opening *g* are cut away as at *h*, each partition beginning at the one adjacent the center partition being gradually cut away to a greater extent to accommodate the enlarged light area from the lamp through the opening *g*.

15 The present invention is designed with the idea that same may be attached to the usual type of lamp, converting same into a "bullet" type of lamp, and also adding thereto the advantages of the protected forward rays and the lateral rays. In the event that the device is used as an attachment for the ordinary lamp, it will be obvious that same could be attached by utilizing a threaded ring which might be attached to the lamp 20 body by any suitable means, the attachment being threaded thereto. In the event that an ordinary lamp is not converted into the present form, an entire lamp is manufactured as a unit, the sectional construction 25 comprising a lamp chamber *a* and a shell *b* will permit the removal of the lens *e* for the arrangement of a new globe or for the adjustment of a reflector. If desired, the 30 chamber *a* and the shell *b* could be made in

one piece with the vertical partitions *c* removable from the shell and the lens *e* held in place by any suitable means.

What I claim as new and desire to secure by Letters Patent, is:—

1. A lamp including a body provided with a source of light and a lens, a shell extension connected to the body outwardly of said lens, said shell extension having an opening in its wall, and partitions in said shell extension coinciding in length with the latter, only such portions of the partitions positioned in the line of travel of the light rays from their source to the lateral opening being cutaway in varying amounts, which progressively increase as they approach the said opening, to permit the passage of light through the opening.

2. A lamp including a body provided with a source of light, a shell extension connected to the forward end of the body, such shell extension having an opening in its wall and intermediate its ends, and partitions in said shell extension having their rear and front edges terminating on lines disposed at right angles to the longitudinal axis of the shell extension, such portions of the partitions positioned in the line of travel of the light rays from their source to the opening in the wall of the shell extension being cut away to permit the passage of light through the opening.

In testimony whereof I affix my signature.
SILAS CORDES.
